A. ROSENBERG,
VARIABLE SPEED FEEDING MECHANISM.
FILED DEC. 19, 1921.

Arthur Rosenberg Inventor

By his Attorney

Martin Joachimson

UNITED STATES PATENT OFFICE.

ARTHUR ROSENBERG, OF NEW YORK, N. Y., ASSIGNOR TO MAURICE J. WOHL, OF BROOKLYN, NEW YORK, MAX MAYER AND ARTHUR ROSENBERG, BOTH OF NEW YORK, N. Y., TRUSTEES.

VARIABLE-SPEED FEEDING MECHANISM.

Application filed December 19, 1921. Serial No. 523,535.

To all whom it may concern:

Be it known that I, ARTHUR ROSENBERG, a citizen of the United States, and residing at 58 West 118th St., New York city, in the county and State of New York, have invented certain new and useful Improvements in Variable-Speed Feeding Mechanism, of which the following is a specification.

10 This invention relates to improvements in feeding mechanisms in which a bar or rod is moved longitudinally at variable speed.

It is the object of this invention to provide a simple feeding device which may be 15 operated by hand or by automatic means to feed a bar longitudinally at instantly variable speed.

It is another object of the invention to provide means for reversing the direction 20 of feeding instantly and for varying the speed of feeding instantly in either direction.

It is another object of this invention to provide means for feeding a rotating cylinder forward or backward at varying speed, 25 without reversing the direction of rotation of said cylinder.

Further objects will appear from the detailed description.

The invention consists in a novel combination of parts and details of construction, 30 hereinafter fully described and illustrated in the accompanying drawings and finally pointed out in the claims.

In the drawings which form a part of 35 these specifications—

Fig. I is a front elevation of the variable speed feeding mechanism. Frame 23 is shown in section on the line I—I of Fig. II. Solenoid 37 is omitted for clearness.

40 Fig. II is a plan view of the mechanism from which top plate 15 is removed; showing frame 23 in section on line III—III of Fig. I.

Fig. III is a vertical side elevation on the 45 line III—III of Fig. I.

Fig. IV is a front elevation showing the principal part of a modification of the same device. The lower part is shown in section on line IV—IV of Fig. V.

50 Fig. V is a plan view on the line V—V of Fig. IV.

Fig. VI is a diagrammatic front elevation showing a detail of the device arranged for operation by a centrifugal governor.

Similar characters of reference indicate 55 corresponding parts throughout the various views.

Referring to Fig. I of the drawings 1 represents an electric motor suitably mounted on base plate 2 and adapted to rotate pulley 3 provided with cogs 4 uniformly spaced on its cylindrical surface and engaging apertures 5 of a steel belt 6 which drives a similar pulley 7 held on an elongated pinion 8 which is rotatably mounted on pivots 9 in 60 bearings 10 and 11. Two side plates 13 and 14 are supported on base 2 and hold a top plate 15. Two horizontal bars 16 are held by plates 13 and 14, they form guides for a journal hanger 17, in which a hollow cylinder 18 is rotatably mounted. On one side of the journal 18 this cylinder carries gear 19 which meshes with the elongated pinion 8, while the other end of cylinder 18 is formed into spring chuck 20. A cylindrical bar 21 70 is held in spring chuck 20 and guided to slide in an aperture 22 of plate 13. A rectangular frame 23 which surrounds bar 21 is arranged near plate 13 to oscillate about the vertical axis formed by pivots 24 and 75 25 held in bearings 26 and 27. A forked lever 28, pivoted to oscillate vertically on frame 23 supports a guide-wheel 30 preferably provided with a knife edge on its circumference. The edge of wheel 30 is held 80 in contact with bar 21 by means of spring 31, suitably fastened to frame 23 and by arm 34 to lever 28. Rod 21 rests on a rotatable cylinder 29, pivoted in frame 23. The free end of arm 34 is connected by 85 means of a forked connecting rod 35 to armature 36 which forms the core of solenoid 37. A spring 38 attached to plate 14 and armature 36 tends to pull the latter towards 90 this plate.

95 A modification of this device is shown in Fig. IV.

In this arrangement the rod 21 is provided with an extension 40 of square cross-section which is slidably held in an aperture 22 of 100 plate 13. An axial pivot 41 provides a journal for rod 21 and the pivot end of a screw 42 held in bar 21 may rotate in a circular recess of 41.

In Fig. IV the lower pivot for frame 23 105 is extended by means of rod 43 through plate 39 and its bearing held on base plate 2 and an armature 44, having the form of

a cylinder provided with two parallel sides, is fastened to axis 43. This armature is oscillatably arranged in the magnetic field of a horseshoe electro-magnet 45 as shown in Fig. V. Two flat springs 46 held on plate 39 bear lightly against the flat sides of frame 23 to hold the same normal to rod 21. A further modification of the mechanism is diagrammatically shown in Fig. VI. In this case a bell crank 50, pivoted on a pin 51 to swing in a vertical plane is connected by means of a pin 52 and eye 53 to frame 23 of the device illustrated in Figs. I, II, III. The eye 53 forms the end of a vertical rod 54 which may slide and rotate in sleeve 55 of crank 50. The horizontal arm of crank 50 is forked to embrace collar 56 of a centrifugal governor 60; two pins 57 held by this fork slide in a groove of this collar. A pulley 61 held on central rod 62 of governor 60 is adapted to receive motion from any suitable source of power by means of a belt and to rotate the governor thereby.

This device is intended to move the cylindrical bar 21 or in Fig. IV the square bar 40, longitudinally forward or backward at a variable rate of speed. This speed may be varied by hand, by variations of an electric current, or by automatic mechanical means. This is accomplished in the following manner:

The pinion 8 is rotated by means of pulleys 3 and 7 and belt 4 at a constant speed from motor 1. This rotary motion is transmitted to bar 21 by means of gear 19. Guide-wheel 30 will inscribe a circle on bar 21 when frame 23 stands perpendicular to rod 21, and this bar will simply rotate without any longitudinal motion. Should however frame 23 be turned on its axis and guide-wheel 30 assume an angular position to rod 21, then this wheel will inscribe a helix upon rod 21 and propel the rod forward if the rotation is in the direction of the arrow "a" and frame 23 is swung in an angular direction towards *a-a*. The rod will move backward if the angular direction of the frame 23 and wheel 30 is towards *b-b*.

The speed with which the rod 21 is propelled varies as the tangent of the angle formed by the guide wheel 30 and the axis of rod 21. This variation can be effected by turning frame 23 by hand, by automatic mechanical devices, for instance as shown in Fig. VI by a centrifugal governor; or by electrical means as shown in Figs. I to V.

While in Figs. I to III the angular movement of frame 23 and guide-wheel 30 is derived from a longitudinal reciprocating movement of a solenoid core, Figs. IV and V show a construction in which this angular movement is produced by an oscillatable armature 44 held on axis 43, which simplifies the mechanical construction of the device.

In some applications of this variable-speed feeding mechanism it is particularly desirable to vary the speed of a longitudinally movable rod which rotates at a constant speed, but in other applications it can be used as a speed varying mechanism for a sliding but not rotating bar, as shown in Fig. IV. On account of its simplicity and sensitiveness it is advantageously used for varying the rate of operation of an iris dia- 75 phragm shutter on moving picture cameras to open or cover the same fraction of lens area during equal time intervals.

The electric current passing through solenoid 37 or magnet 45 can be varied by remote control and thereby the speed of rod 21; but it is evident that the rod 21 itself can be made the controlling agent for this current. This is illustrated in a separate application for Letters Patent for an electric 85 arc lamp, in which this device is used as a feeding mechanism for the carbon electrodes.

Having thus described my invention, what I claim as new and desire to secure by Letters Patent is:

1. In a device of the kind described, a cylinder, means to rotate said cylinder on its axis, means to describe a helix upon the surface of said cylinder to move the same longitudinally and magnetic means to vary the pitch of said helix during the rotation.

2. In a device of the kind described, a cylinder, means to rotate said cylinder on its axis, means to inscribe a helix on said cylinder and electrically operated means to vary the angle of said helix during the rotation to move said cylinder longitudinally at varying speed.

3. In a device of the kind described a cylinder, means to rotate said cylinder on its axis, means describing a helix upon the surface of said cylinder to move the same longitudinally during its rotation and to reverse the longitudinal movement of said cylinder during its rotation in the same direction and automatic means to control the movements of said cylinder.

4. In a device of the kind described, a cylinder, means to rotate said cylinder on its axis, means describing a helix upon the surface of said cylinder to move the same longitudinally, and automatic means to vary the angle of said helix and the speed of longitudinal movement of said cylinder.

5. In a device of the kind described, a cylinder, means to rotate said cylinder on its axis, means inscribing a helix upon said cylinder to move the same longitudinally during its rotation, said inscribing means being adapted to vary the speed of said longitudinal movement and remotely power controlled means to operate said inscribing means.

6. In a device of the kind described, the

- combination with a rotatable cylinder and a disk to inscribe a helix of variable angularity thereon during its rotation, of a bar in coaxial alinement with said cylinder and 5 means to prevent rotation of said bar, said cylinder and said disk forming means to move said bar longitudinally at variable speed.
7. In a device of the kind described, a cylinder, means to rotate said cylinder on its axis, a guide plate angularly disposed to said axis in frictional engagement with said cylinder, and automatic means to vary the angular position of said guide plate to describe 10 a helix of varying pitch upon said cylinder to move said cylinder longitudinally at varying speed.
8. In a device of the kind described, a cylinder, means to rotate said cylinder on its axis, an oscillatable frame surrounding said cylinder, a guide plate held by said frame in frictional engagement with said cylinder, power operated means to oscillate said frame and said guide plate to describe a helix upon 15 said cylinder during its rotation, forming automatic means to move said cylinder longitudinally in alternate direction while rotating in the same direction.
9. In a device of the kind described, a cylinder, means to rotate said cylinder on its axis, a disk in frictional engagement with said cylinder on an axis normally parallel to that of said cylinder to describe a circle upon the cylindrical surface power operated, 20 means to vary the inclination of said disk axis to describe a helix upon said cylinder during its rotation and forming automatic means to produce and to control longitudinal movement of said cylinder.
- 40 10. In a device of the kind described, a cylinder, means to rotate said cylinder on its axis, a disk in frictional engagement with said cylinder to be rotated thereby upon an axis normally parallel to the cylinder axis, means to oscillate said disk on an axis per- 45 pendicular to the axis of rotation and remotely power controlled means to produce said oscillation.
11. In a device of the kind described, the combination with a rotating cylinder and 50 means inscribing a helix of variable pitch thereon to move said cylinder longitudinally at variable speed, of a journal moved by said cylinder and forming a support for the same.
12. In a device of the kind described, the 55 combination with a rotating cylinder and means to describe a helix of variable angularity thereon to move said cylinder longitudinally at variable speed, of a travelling support moved by said cylinder and means 60 to rotate said cylinder held by said support.
13. In a device of the kind described the combination with a rotating cylinder and a disk describing a helix of variable angle 65 thereon during the rotation to vary the speed of longitudinal movement, of a support for said cylinder moved by the same and rotatable clamping means to hold said cylinder on said support.
14. In a device of the kind described a cyl- 70 inder, means to rotate said cylinder on its axis, an oscillatable frame surrounding said cylinder, means held by said frame to inscribe a helix of variable angle on said cylinder to vary its speed of longitudinal move- 75 ment and a supporting roller rotating on an axis transversely of said cylinder held by said frame.
15. In a device of the kind described a cyl- 80 inder, means to rotate said cylinder on its axis, a frame oscillatable on an axis trans-verse to said cylinder supporting means to inscribe a helix of variable angle on said cylinder and a solenoid to operate said frame.

ARTHUR ROSENBERG.
